EUGENE GROSJEAN, OF PITTSBURG, PENNSYLVANIA, ASSIGNOR TO HIMSELF, JACOB WEAVER, JR., AND ALFRED H. JONES.

Letters Patent No. 88,564, dated April 6, 1869.

IMPROVEMENT IN BARREL-TRUCKS.

The Schedule referred to in these Letters Patent and making part of the same.

To all whom it may concern:

Be it known that I, EUGENE GROSJEAN, of the city of Pittsburg, county of Allegheny, and State of Pennsylvania, have invented a new and useful Improved Barrel-Roller, or Truck, which is of great utility and convenience, and in the use of which time and labor are saved; and in order to convey a knowledge of the practicable operation of the same to those skilled in the principles thus applied and combined, I hereby declare the following to be a full and exact description of the same, reference being had to the accompanying drawing, and to the letters and figures marked thereon.

The drawing is a perspective view of the machine.

The machine may be made of wood or metal.

A are the handles, or the end of the levers.

B is the bolt, or fulcrum which holds the levers together, and upon which they move.

The holes in each lever are for changing the bolt B, to enlarge or diminish the opening of the flanges, or jaws C C, according to the size of the barrel to be handled.

D is a cam-clasp.

E is a strap.

F is a ring on the end of the strap E.

By loosing the cam-clasp D, the strap E is released, when, by pulling the levers A apart, the flanges, or jaws C C open.

When thus open, and held over a barrel, by catching the ring F, pulling the strap tight, compresses the ends of the levers A and C.

Now, by turning the cam-clasp D over, or tight down on the strap E, the lever is firmly attached to the barrel, the flanges, or jaws C C shut fast against its heads, and it is held immovable by small teeth-points, projecting on the inside of the flanges, or jaws, marked in the drawing 1, 2, and 3—one at each of their triangles.

The barrel, keg, or log thus caught tight, can be rolled, pushed, or pulled in any direction.

The flanges, or jaws C C are made loose and movable, with a hole in the centre, marked figure 4, and are attached to the ends of the levers through these holes, by riveting or otherwise.

The flanges revolve, but cannot get off these ends of the levers.

The flanges may be made any shape, with or without the teeth-points.

These ends form the axle upon which the flanges, or jaws revolve, with the barrel or cylinder, kegs or logs.

Having now described my invention,

What I claim as my invention, and desire to secure by Letters Patent of the United States, is—

The attached strap E, combined with the cam-clasp D, in their action with the levers A, bolt B, and flanges, or jaws C C, as shown, for the purposes set forth, substantially as described.

EUGENE GROSJEAN.
